UNITED STATES PATENT OFFICE

JOHN B. RUSS, OF SHELTON, CONNECTICUT, ASSIGNOR TO THE BASSETT METAL GOODS COMPANY, INC., OF DERBY, CONNECTICUT, A CORPORATION OF CONNECTICUT

DESIGN FOR A WARDROBE-TRUNK LOCK OR SIMILAR ARTICLE

Application filed February 16, 1929. Serial No. 30,086. Term of patent 3½ years.

To all whom it may concern:

Be it known that I, JOHN B. Russ, a citizen of the United States, residing at Shelton, in the county of Fairfield and the State of Connecticut, have invented a new, original, and ornamental Design for a Wardrobe-Trunk Lock or Similar Article, of which the following is a specification, reference being had to the accompanying drawing, forming part thereof.

In said drawings, Figure 1 is a face view, and Figure 2 is a side edge view of a wardrobe trunk lock or similar article, showing my new design.

I claim:—

The ornamental design for a wardrobe trunk lock or similar article as shown.

Dated this 9th day of February, 1929.

JOHN B. RUSS.
